WRAPPER OR CARTON

Louis A. Nahm and John F. Nahm, St. Louis, Mo.

Application February 28, 1936, Serial No. 66,247

5 Claims. (Cl. 229—17)

This invention relates to wrappers or cartons.

Objects of the invention are to provide an improved device that may be used satisfactorily as a wrapper or carton and, when used as a wrapper, may enclose a package comprising a container and its contents, which contents may be exposed through an opening provided in one wall of the wrapper by sliding a portion thereof to form said opening, and which may be similarly employed to provide an opening for access to the contents when used as a carton proper; to provide an improved closure for an opening through one wall of the wrapper or carton and a hinged device connecting said closure with another portion of the wrapper or carton by manipulation of which the closure may be operated; and to provide improved means for guiding and retaining the closure in proper position.

Another object of the invention is to provide a wrapper or carton embodying the improved features of construction and the advantages of operation herein disclosed, reference being made to the annexed drawing, in which—

Fig. 1 is a perspective view of our improved wrapper or carton in complete assembly and closed.

Fig. 2 is a similar perspective view showing the closure for the opening at one end of the wrapper or carton in position to provide said opening to permit access to the contents.

Fig. 3 is a vertical transverse sectional view along the line 3—3 of Fig. 1.

Fig. 4 is a plan view of the blank from which the improved wrapper or carton is formed.

As shown, in Fig. 4, the blank is a unitary member shaped so that, when folded along appropriate lines or pivotal connections, the sections thereof will form the different walls of the wrapper or carton. Specifically, the blank includes at one end a wall section 1 integrally connected with an opposite wall section 2 by a relatively narrow end wall section 3 which is defined from the wall section 1 by a fold or score line 4 and from the wall section 2 by a fold or score line 5. Attaching portions 6 and 7 are integrally connected with the ends of the wall sections 1 and 2, respectively, and defined therefrom by fold or score lines 8 and 9.

The wall section 1 is integrally connected with and defined from a wall section 10 by a fold or score line 11; the wall section 10 is integrally connected with and defined from a wall section 12 by a fold or score line 13; the wall section 12 is integrally connected with and defined from a wall section 14, matching the wall section 10, by a

fold or score line 15; and the wall section 14 is integrally connected with and defined from a wall section comprising strips 16 and 17 by a fold or score line 18. The strips 16 and 17 are pivotally connected by a fold line or hinge 19. The opposite ends, respectively, of the wall sections 1, 10, 12, 14, 16 and 17 are in alinement. That end of the strip 17 which is in alinement with the corresponding end of the wall section 1 is integrally connected with a wall section 20 by a fold or score line 21, and said wall section 20 is integrally connected with a tab 22 by a fold or score line 23.

In assembling or forming this blank into a wrapper or carton, the wall section 14 is folded along the line 15 to a position at right angles to the wall section 12; the composite wall section comprising the strips 16 and 17 is folded to position parallel with and opposite from the wall section 12 along the line 18; and the wall section 20 is folded over toward the wall section 12 along the line 21, and the tab 22 is folded downwardly against the inner side of the wall section 12. Thus, the wall section 12 and the composite wall sections 16 and 17 are separated from each other by the width of the wall section 14 and of the wall section 20. Then, the wall section 10 is folded upwardly at right angles to the wall section 12 along the line 13 and against the edges of the strip 17 and the wall section 20; the wall section 1 is then folded over and against the outer surface of the strips 16 and 17. The narrow wall section 3 is folded over across the ends of the wall section 12 and the strip 16; the wall section 2 is folded along the line 5 against the wall section 12; and the attaching portions 6 and 7 are folded toward each other and in superimposed relationship and attached together.

Thus, the wall section 1 and the wall section comprising the strips 16 and 17 are relatively slidable, and the tab 22 holds the wall section 20 in proper position to close the opening 24 provided by the space 25 between the ends of the wall sections 1 and 2. The wall section 1 may be formed with a notch 26 to permit engagement of the thumb or finger of the user with the strip 16 so as to move the connected portions 16, 17, 20 and 22 from the positions they occupy in Fig. 1 to the positions disclosed in Fig. 2 of the drawing.

As specifically shown, the device is used as a wrapper for a package 27 of cigarettes, the cigarettes being shown in their original wrapper or enclosure, which has been opened at one end so

as to permit removal of the cigarettes individually through the opening 24.

If desired, the wrapper or carton may be opened at one edge by withdrawing the composite wall section 16, 17, the wall 20 and the tab 22 entirely from within the wrapper or carton to permit insertion of new contents, such as a new package of cigarettes, and then these wall sections and the tab may be again inserted 10 as in Figs. 1 and 2.

From the foregoing it should be apparent that our improved wrapper or carton comprises the five walls 1, 2, 3, 6 and 10 forming an enclosure; that the wall 3 has an opening 24 for removal of 15 contents from the enclosure; that the hinged wall 14 is provided for closing the open side of the enclosure opposite from the wall 10; and that the wall 20 is connected with the hinged wall 14 through the parts 17 and 16 and is movable 20 thereby to positions to close and to open the opening 24.

Our improved wrapper or carton may be made from different forms of blanks, and the one shown is for purposes of illustration only. The device 25 may be applied to various uses other than the uses specifically suggested, and we do not restrict ourselves in these or other unessential particulars, but what we claim and desire to secure by Letters Patent is:—

30. 1. A wrapper or carton comprising five walls forming an enclosure open at one side and one of said walls having an opening for removal of contents from said enclosure, a hinged wall for closing said open side of said enclosure, and a 35 wall connected with said hinged wall and movable thereby to positions to close and to open said opening.

2. A wrapper or carton comprising a number of attached walls forming an enclosure open at one

side and one of said walls having an opening therethrough for the removal of contents from said enclosure, a closure for said opening, and a hinged wall closing said open side of said enclosure for moving said closure to and from position 5 to close and to open said opening.

3. A polygonal wrapper or carton comprising a plurality of walls forming an enclosure open at one side and one of said walls having an opening for removal of contents from said enclosure, a 10 hinged wall for closing the open side of said enclosure and movable to and from position to close said open side, a wall in connection with said hinged wall and movable thereby to positions to close and to open said opening, and means for 15 holding said hinged wall in position in which it will retain said last named wall in position to close said opening.

4. A polygonal wrapper or carton comprising a series of integrally united walls forming an enclosure 20 open at one side and one of which walls has an opening into the enclosure to permit removal of contents therefrom, and walls pivotally connected with one of said walls and movable to positions to open and to close said open side of 25 said enclosure and said opening.

5. A wrapper or carton comprising wall elements forming an enclosure open at one side and having an opening through one of said wall elements spaced from said open side, a hinged wall 30 element for closing said open side, and a wall in connection with said wall element and operated thereby to positions to close and to open said opening when said wall element is operated to positions to close and to open said open side of 35 said enclosure.
